UNITED STATES PATENT OFFICE

GUY M. FRENCH, OF RENFREW, ONTARIO, CANADA

DOOR OPERATING MEANS

Application filed December 22, 1930, Serial No. 503,992. Renewed October 2, 1931.

This invention relates to door opening mechanism and has for its principal object the provision of means whereby double doors, such as garage doors, may be swung simultaneously to open or closed position.

Another object is the provision of means whereby the operating mechanism may be actuated from a distance.

Another object is the provision of means whereby the doors will be fixedly retained in either open or closed position.

With these and other objects in view as will appear as the description proceeds, the invention consists of the novel construction, combination and arrangement of co-operating elements as hereinafter more specifically set forth, claimed and shown in the accompanying drawing forming a part of the present application, in which:

20 The figure is a top plan view of the preferred embodiment of my invention.

Like numerals of reference designate corresponding parts throughout the different views.

25 1 is a guide bar mounted for reciprocal and lateral movement in guide brackets 2 and 3, which guide brackets are supported from the ceiling of a garage or suitable platform. The forward end of the guide bar 1 is notched 30 at one corner as at 4. Adjacent the rear end of the guide bar 1 is a notch 5, the purpose of which will presently be disclosed. Connected to the forward end of the guide bar 1 is a flexible pull member 6, which pull member extends forwardly at an angle and is 35 trained around the pulley 7, around the pulley 8 and forwardly through an opening 9 in the front wall of the garage. The flexible member 6 may be extended a predetermined 40 distance in advance of the front of the garage and provided with a suitable ring or handle.

Connected to the rear end of the guide bar 1 is a flexible pull member 10, which is trained over the pulley 11, pulley 12 and extended 45 forwardly through the opening 9 to a position adjacent the free end of the flexible member 6. The free end of the member 10 may be provided with a suitable ring or handle.

50 14 and 15 are connecting rods pivotally connected at one end by means of the bolt

16 to the guide bar 1, the opposite ends of the connecting rods 14 and 15 are pivotally connected, by means of the bearing brackets 17 and 18, to the doors 19 and 20 respectively. Secured, preferably, to the bracket 3 is a leaf-spring 21, the free end of which compressively contacts with the side of the guide bar 1. Connected preferably to the guide bracket 2 is a leaf-spring 22, the free end of which compressively contacts with the side of the guide bar 1.

When the doors are in closed position, the guide bar is in position as shown in full lines in the drawing, a portion of the bracket 3 registering in the notch 4 of the guide bar 1 and the forward end of the guide bar 1 is restrained from lateral movement by means of the leaf-spring 21. In this manner the doors 19 and 20 are retained in closed position through the medium of the bearing brackets 17 and 18, connecting rods 14 and 15, bolt 16 and guide bar 1.

When it is desirous of opening the doors 19 and 20, the flexible member 6 will be pulled in the direction of the arrow and, as the same is pulled, the forward end of the guide bar 1 will be pulled sidewise against the compression of the leaf-spring 21 until the guide bracket 3 is free of the notch 4. The guide bar 1 will now be pulled forwardly until the notch 5 at the rear end thereof registers with the guide bracket 2. As the notch 5 registers opposite the guide bracket 2, the leaf-spring 22 will move the rear end of the guide bar 1 sidewise to engage the side of the bracket 2 in the notch 5 and will retain the guide bar 1 in position as shown in dotted lines. As the guide bar 1 is moved forwardly, as just hereinbefore described, the doors 19 and 20 will be moved from the position as shown in full lines to the open position as shown in dotted lines through the medium of the bolt 16, connecting rods 14 and 15 and bearing brackets 17 and 18, and will be retained in fixed open position through the engagement of the side of the bracket 2 in the notch 5. When it is desirous of closing the doors 19 and 20, the flexible pull member 10 will be pulled and as the same is pulled, the rear end of the guide bar 1 will be moved

sidewise to disengage the bracket 2 from the notch 5. The guide bar 1 will now be pulled rearwardly until the notch 4 registers with the side of the bracket 3 when the leaf-spring 21 will cause the forward end of the guide bar 1 to move sidewise to engage the side of the bracket 3 in the notch 4. As the guide bar thus moves rearwardly, the doors 19 and 20 will be moved from the position as shown 10 in dotted lines to the closed position as shown in full lines, through the medium of the bolt 16, connecting rods 14 and 15 and bearing brackets 17 and 18. The respective connections between the connecting rods 14 15 and 15 and the bearing brackets 17 and 18 and the guide bar 1 may be sufficiently loose to allow the side play of the guide bar 1 during opening and closing operations.

The foregoing specifications and annexed 20 drawing disclose the preferred embodiment of my invention, but it is to be understood that minor changes may be resorted to in the commercial adaptation of my invention without departing from the scope of the invention 25 as hereinafter claimed.

What I claim as new is:

1. Mechanism for operating doors, comprising guide brackets; a guide bar mounted for reciprocal and lateral movement in 30 said guide brackets; connecting rods pivotally connected at one end to said guide bar and at their opposite ends to said doors respectively; a notch formed in the side of and adjacent the forward end of said guide bar 35 adapted to engage with one of said brackets when said doors are in closed position; a notch formed in the side of and adjacent the rear end of said guide bar adapted to engage with one of said guide brackets when 40

said doors are in open position; means for retaining the forward end of said guide bar in engagement with one of said brackets when said doors are in closed position; means for retaining the rear end of said guide bar in engagement with one of said brackets when said doors are in open position; means for disengaging the forward end of said guide bar by lateral movement from its respective bracket and for moving said guide bar in a 10 forward direction and means for disengaging the rear end of said guide bar by lateral movement from its respective bracket and for moving said guide bar in rearward direction. 15

2. Mechanism for operating doors, comprising a guide bar mounted for reciprocal movement; connecting rods pivotally connected at one end to said guide bar and at their opposite ends to said doors respectively; a means for moving said guide bar in one 20 direction to cause said connecting rods to open said doors; a means for moving said guide bar in an opposite direction to cause said connecting rods to close said doors; means for locking said guide bar against reciprocal movement when said doors are in closed position and means for locking said guide bar against reciprocal movement when said doors are in open position, said first mentioned means adapted, upon operation 25 thereof, to move the end of said guide bar laterally and render said first mentioned locking means inoperative and said second mentioned means adapted, upon operation thereof, to move the opposite end of said guide 30 bar laterally and render said second mentioned locking means inoperative. 90

In testimony whereof, I affix my signature.
GUY M. FRENCH.
